UNITED STATES PATENT OFFICE.

PATRICK R. WALSH, OF ROCHESTER, NEW YORK, ASSIGNOR OF ONE-HALF
TO MARY CAMPBELL, OF SAME PLACE.

BICYCLE-SEAT SPRING.

SPECIFICATION forming part of Letters Patent No. 469,192, dated February 16, 1892.

Application filed October 12, 1891. Serial No. 408,494. (No model.)

To all whom it may concern:

Be it known that I, PATRICK R. WALSH, of Rochester, in the county of Monroe and State of New York, have invented a new and useful Improvement in Bicycle-Seat Springs, which improvement is fully set forth in the following specification and shown in the accompanying drawings.

My invention relates to the class of springs for bicycle saddles or seats in which the springs are made of round steel rods, bent so as to form a yielding support for the seat, the invention being hereinafter fully described and particularly pointed out in the claims.

Referring to the drawings, Figure 1 is a side elevation of my improved spring, and Fig. 2 a view of the same seen as indicated by arrow in Fig. 1.

The spring I usually make of spring-steel rod, round or polygonal in cross-section, one-half inch in diameter, and bend it substantially as shown in the drawings. It is made, preferably, with a complete turn or coil *a*, and successive spring bends *b* in its upper branch or member *e*, and *c d* in the lower branch *f*.

k is a tang or shank to enter the socket *l* of the bicycle, to be held in the usual manner, and *s* is the stem to enter the hub *p* of the seat. In this construction of the spring the radius *g* of the coil *a* is shorter than the radius *h* of the bend *c*, the radius *h* being in turn shorter than the radius *i* of the bend *d*—that is to say, the radii of the various spring-bends successively decreases in length as they recede from the shank *k* to the extreme overhanging bend or coil *a*. Likewise the radius *n* of the bend *b*, between the bend *a* and the stem *s*, is greater than the radius *g*.

It is understood that in a spring, other things being equal, the shorter the radius of a bend the stiffer is the bend, and in a spring of the nature of the one here shown the material of the spring at the bend *a* is subjected to greater stress of flexure when supporting the weight of the rider than the parts at *c* and *d*, and also the part at *b*; and in

constructing this spring I have distributed 50 the spring-bends, considered as to their relative stiffness, with reference to the points subjected to the different degrees of stress. That is to say, the stiffest bend is placed at the point of greatest stress, the limberest 55 bend at the point of least stress, and the intermediate bend at the point in the spring where the medium stress falls.

The bends at *o* and *r* are formed to give to the shank and stem *s*, respectively, their 60 proper directions, one substantially vertical and the other substantially horizontal, and are not designed especially as spring-bends. By this construction of the spring I render available for spring purposes all of the material from *o* to *r*, thus getting much spring 65 with a comparatively short piece of steel rod and within little weight and in small space.

The bends *b* and *c* are preferably made of the same radius and formed so as to quite 70 clearly approach each other as to vertical distance; but these bends are laterally offset from each other to occupy different vertical planes, on account of which there is no danger of their colliding when from an unusual cause—as, for instance, from the wheel suddenly rolling upon or over some large body in its way—the spring is caused to yield momentarily in excess under the unusual stress brought to bear upon it.

What I claim as my invention is—

1. A bicycle-saddle spring formed of round or polygonal rod, having an extreme coil or bend *a* and spring-bends *c*, *d*, and *b* near the coil, with shank and stem, substantially as 85 shown.

2. A spring for the saddle of a bicycle, formed with spring-bends *d*, *c*, and *a*, shank *k*, and stem *s*, the radii of said spring-bends decreasing in length from the shank outward, substantially as and for the purpose 90 set forth.

3. A bicycle-saddle spring formed with spring-bends *d*, *c*, and *a*, with shank *k* and stem *s*, and a spring-bend *b* between the bend *a* and the stem, said bend *b* having a radius greater than the radius of the bend *a*, substantially as described.

4. A bicycle-saddle spring formed with a spring bend or coil *a* and a bend *b* in its upper branch and a bend *c* in its lower branch, said bends *b* and *c* being made substantially toward and near each other and laterally offset in different vertical planes, substantially as shown and described.

In witness whereof I have hereunto set my hand, this 28th day of September, 1891, in the presence of two subscribing witnesses.

PATRICK R. WALSH.
